US00D973128S

(12) **United States Design Patent** (10) **Patent No.:** **US D973,128 S**
Wang (45) **Date of Patent:** **** Dec. 20, 2022**

(54) **HANDHELD PORTABLE PHOTOGRAPHY TRIPOD**

(71) Applicant: **PGYTECH CO., LTD.**, Jiangsu (CN)

(72) Inventor: **Jun Wang**, Jiangsu (CN)

(73) Assignee: **PGYTECH CO., LTD.**, Kunshan (CN)

(**) Term: **15 Years**

(21) Appl. No.: **29/758,177**

(22) Filed: **Nov. 12, 2020**

(30) **Foreign Application Priority Data**

Sep. 3, 2020 (CN) 202030517533.3
